UNITED STATES PATENT OFFICE.

STEVE CHISMADIA, OF DETROIT, MICHIGAN.

AUTOMATIC RAILROAD SIGNAL.

Application filed June 17, 1925. Serial No. 37,832.

To all whom it may concern:

Be it known that I, STEVE CHISMADIA, a citizen of the United States of America, residing at Detroit, in the county of Wayne and State of Michigan, have invented certain new and useful Improvements in Automatic Railroad Signals, of which the following is a specification.

This invention relates to certain new and 10 useful improvements in automatic railroad signals, and has for its primary object to provide a signal for railroad or other car track crossings to give both an audible and visual signal to indicate the approach to 15 the crossing of a railroad car or the like.

A further object of the invention is to provide an automatic signal of the type above set forth wherein a pendulous signal arm normally hidden from view is adapted 20 to be automatically oscillated or swung to exposed positions to indicate the approach of a train with the signal arm being in the form of a bell which is preferably painted red to be clearly viewable and also sound 25 the alarm when operated.

Another object of the invention is to provide an automatic signal for railroad or street car crossings wherein a single signal arm located at one side of the crossing is operatively connected with train operated trip 30 devices supported on the ties of either single or double tracks, and any number of trip devices desired may be employed and positioned in spaced relations to effect a substantially continuous operation of the signal device 35 during the approach of the train toward the crossing.

With the above general objects in view and others that will appear as the nature of 40 the invention is better understood, the same consists of the novel form, combination and arrangement of parts hereinafter more fully described, shown in the accompanying drawings and claimed.

45 In the drawings, wherein like reference characters designate corresponding parts throughout the several views,

Figure 1 is a diagrammatic top plan view of an automatic railroad crossing signal constructed in accordance with the present invention, showing double tracks, the signal arm or post and train operated trip devices arranged along the tracks,

50 Figure 2 is a perspective view of one of the tracks showing the connected trip devices mounted on the rail supporting ties

and connected together for simultaneous operation with the covers for the trip devices removed,

Figure 3 is a perspective view of the signal post,

Figure 4 is a vertical sectional view, partly broken away, of the signal post normally hidden between a guard hood and illustrated by dotted lines in its oscillated 65 exposed positions,

Figure 5 is an end elevational view of the upper end of the signal post,

Figure 6 is a perspective view of one of the train operated trip devices,

Figure 7 is a vertical longitudinal sectional view through a casing enclosing the trip device or lever,

Figure 8 is a vertical cross-sectional view taken on line VIII—VIII of Fig. 7 showing 75 the trip lever pivotally supported in the side walls of the casing,

Figure 9 is a top plan view of the casing, and

Figure 10 is an end elevational view, 80 partly in section showing a trip arm carried by a train or car moving through the slotted upper end of the casing for engaging the trip lever.

Referring more in detail to the accompanying drawings, the reference numeral 1 designates the usual railroad ties for supporting the rails 2 and with which track structure visual and audible signal devices are associated to be arranged adjacent crossings.

The signal device includes a tubular post 3 mounted upon a base block 4 and carrying an elbow fitting 5 at its upper end to which a horizontal tubular arm 6 is connected. The outer end of the tubular arm 6 is split at its lower side and spread apart as shown in Fig. 5 and a guard hood 7 overlying the outer split end of the arm 6 carries depending guard plates 8.

A signal arm in the form of an oscillating or swingingly mounted bell 9 carries side arms 10 at its upper end that are fixed to the shaft 11 journaled in the side walls of the outer end of the tubular arm 6 and said shaft 11 carries a sprocket wheel 12 intermediate the ends thereof as shown in Figs. 4 and 5. A sprocket chain 13 passes over the sprocket wheels 12 and has one end thereof secured to a coil spring 14 that is 105 anchored as at 15 within the tubular arm 6. A cord or cable 16 attached to the other end

of the sprocket chain passes over a guide pulley 17 mounted in the elbow connection 5, the cable 16 passing downwardly through the tubular post 3 and around the guide pulley 18 at the lower end of the post to pass therefrom through the opening 19 for attachment to the train operated trip devices arranged along the track. The bell 9 is preferably painted red so that when the same is operated in a pendulous manner, the same swings laterally of the guard walls 8 to expose the same to view as illustrated by dotted lines in Fig. 4 and also for giving an audible signal.

One form of trip device is shown in Figs. 2 and 6 and includes angle supports 20 having the base portions 21 secured to the ties 1 with the trip lever 22 pivotally supported as at 23 between the upper ends of the angle supports. The pivotal supports 23 for the trip levers are disposed above the transverse median lines thereof to permit increased swinging movement for the lower ends of the trip levers. A laterally resilient trip arm 24 carried by a support 25 that may be mounted upon the front and rear ends of a train or a car is moved into engagement with the upper end of the trip lever 22 for operating the same. As shown in Fig. 2 the trip devices or levers are arranged in spaced relations along the track and are connected by cords or cables 26 having end relatively short flexible chain connections 27 with the lower ends of the trip levers, the several trip levers being connected in series so that movement of the trip lever first engaged by the trip arm 24 will be transmitted through the entire series. As shown in Figs. 1 and 3 the cables 26 are attached as at 28 to the cable 16 for operating the signal arm 9. If desired, the first one of the series of trip devices as shown in Fig. 1 may have a spring connection 29 between the lower end of the trip lever and an adjacent tie, this spring 29 being preferably employed on a one-way track and cooperating with the spring 14 in the tubular arm 6 of the signal post for normally holding the signal arm 9 vertically positioned as illustrated by full lines in Fig. 4.

It will therefore be seen that a train or car approaching the crossing will have the trip arm 24 carried thereby in a position to contact the trip lever 22 for operating the same with the cables 26 and 16. A pull upon the cable 16 will operate the sprocket chain 13 against the tension of the spring 14 to rotate the shaft 11 and signal arm 9 in the form of a bell carried thereby to shift the bell laterally of the guard walls 8. The weight of the bell combined with the functioning of the two springs 14 and 29 will cause the bell to swing backwardly and forwardly to exposed positions at each side of the guard walls 8 as indicated by dotted

lines in Fig. 4 to give an audible signal while movement of the bell and its color will attract attention thereto. The bell 9 will be substantially continuous in its operation effected by the trip arm 24 successively engaging the several trip levers 22 and as the pivotal supports 23 for the trip levers are arranged adjacent the upper ends thereof, a wider throw of movement will be given the lower end of each trip lever. As indicated in Figs. 1 and 3, a single signal post may be operated by trip devices arranged along one or more tracks with each series of trip devices having a cable connection 26 with the cable 16 that is connected to the signal arm.

In the form of the invention shown in Figs. 7 to 10, the trip levers are each pivotally supported in a casing having side walls 30 and end walls 31, the casing having base flanges 32 for supporting the same upon the ties 1. The upper wall 33 of the casing is longitudinally slotted as at 34 with the outer ends of the slots enlarged as at 35 and shown more clearly in Fig. 9. A shaft 36 supported in the side walls 30 of the casing pivotally supports the trip lever 22 and pipe sections 37 connected to the end walls 31 of the casing constitute guides for the cables 26 and chains 27. The trip arm 24 carried by the train or car is laterally resilient and is initially received in the widened end 35 of the slot 34 to be correctly guided to and through the slot for engagement with the trip lever 22 as shown in Fig. 10.

From the above detail description of the invention, it is believed that the construction and operation thereof will at once be apparent, it being noted that the signal post may be of the desired height and the signal arm or bell 9 of a size that when operated the signal will be audibly and visually given in a most efficient manner. It is also to be noted that the signal device is operated when trains or cars travel in either direction over the track and that the spring devices associated with the cables normally retains the signal arm or bell in a hidden position.

While there are herein shown and described the preferred embodiments of the present invention, it is nevertheless to be understood that minor changes may be made therein without departing from the spirit and scope of the invention as claimed.

What is claimed as new is:

1. In an automatic railroad signal, an audible and visual pendulous signal arm, train operated trip devices, cable connections between the trip devices and signal arm, a guard for normally holding the signal arm in an unexposed position, and springs associated with the cable for arresting movement of the signal arm when the trip devices are out of operation.

2. In an automatic railroad signal, an audible and visual pendulous signal arm, train operated trip devices, cable connections between the trip devices and signal arm, springs associated with the cable for arresting movement of the signal arms when the trip devices are out of operation, each trip device including a lever pivotally supported adjacent its upper end to permit a longer movement at the lower end and cables connecting the lower ends of the trip levers.

3. In an automatic railroad signal, an audible and visual pendulous signal arm, train operated trip devices, cable connections between the trip devices and signal arm, a guard for normally holding the signal arm in an unexposed position, springs associated with the cable for arresting movement of the signal arm when the trip devices are out of operation, each trip device including a lever pivotally supported adjacent its upper end to permit a longer movement at the lower end, and cables connecting the lower ends of the trip levers.

4. In an automatic railroad signal, an audible and visual pendulous signal arm, train operated trip devices, cable connections between the trip devices and signal arm, springs associated with the cable for arresting movement of the signal arms

when the trip devices are out of operation, each trip device including a lever pivotally supported adjacent its upper end to permit a longer movement at the lower end, cables connecting the lower ends of the trip levers, a casing for each trip lever having a slotted upper wall with the opposite ends of the slot enlarged and a laterally resilient trip arm adapted to be moved through the slot for engagement with the upper end of the trip lever.

5. In an automatic railroad signal, an audible and visual pendulous signal arm, train operated trip devices, cable connections between the trip devices and signal arm, a guard for normally holding the signal arm in an unexposed position, springs associated with the cable for arresting movement of the signal arm when the trip devices are out of operation, each trip device including a lever pivotally supported adjacent its upper end to permit a longer movement at the lower end, cables connecting the lower ends of the trip levers, a casing for each trip lever having a slotted upper wall with the opposite ends of the slot enlarged and a laterally resilient trip arm adapted to be moved through the slot for engagement with the upper end of the trip lever.

In testimony whereof I affix my signature.
STEVE CHISMADIA.
